UNITED STATES PATENT OFFICE.

JAMES E. AUSTIN, OF BINGHAMTON, NEW YORK.

SAD-IRON.

No. 851,479.

Specification of Letters Patent.

Patented April 23, 1907.

Application filed September 7, 1905. Serial No. 277,394.

To all whom it may concern:

Be it known that I, JAMES E. AUSTIN, a citizen of the United States, and a resident of the city of Binghamton, in the county of 5 Broome and State of New York, have invented a new and Improved Sad-Iron, of which the following is a full, clear, and exact description.

The invention relates to sad-irons heated 10 by burning gas, and its object is to provide a new and improved sad-iron which is exceedingly simple and durable in construction and arranged to insure a uniform heating with a minimum consumption of gas and to 15 produce a complete combustion of the gas, to render the use of the sad-iron very economical and practically odorless.

A practical embodiment of the invention is represented in the accompanying drawings 20 forming a part of this specification, in which similar characters of reference indicate corresponding parts in all the figures.

Figure 1 is a longitudinal sectional side elevation of the improvement, on the line 1—1 25 of Fig. 2; Fig. 2 is a transverse section of the same, on the line 2—2 of Fig. 1; Fig. 3 is a sectional plan view of the same, on the line 3—3 of Fig. 1; and Fig. 4 is a cross-section of the vaived air inlet for the Bunsen burner, the section being on the line 4—4 of Fig. 1.

The body A of the sad-iron is shown as of the usual shape and made of two castings, one of which is hollow and comprises the bottom A', and the sides A² which converge 35 and meet at the front of the body, and the other casting comprises the top A³, the rear end A⁴ and the draft-flue A⁵ at the forward end of the top A³, the two castings being securely fastened together by screws B. The 40 draft flue is closed in front and provided with lateral outlets a⁶ one at each side. On the rear end of the body A is formed a boss A⁶ into which screws the end of the mixing chamber C' of a Bunsen burner C, having the 45 usual gas pipe C², connected by a hose D with a gas supply in the usual manner, the said gas pipe C² being provided with a regulating cock C³ for regulating the amount of gas admitted to the mixing chamber C'. The latter is provided with suitable air-intake openings C⁴ controlled by a valve C⁵ under the control of the operator, to admit more or less air to the mixing chamber. The valve C⁵ is in the form of a sleeve mounted to turn on 55 the mixing chamber C' over the openings of said chamber. By use of the cock C³ and

the valve C⁵, the proper amounts of gas and air are admitted to the mixing chamber to insure a highly combustible mixture of gas and air.

The boss A⁶ extending at the middle of the rear end A⁴ is inclined inwardly and downwardly to direct the flame of the Bunsen burner in a like direction, and is provided with an enlarged spreading aperture a⁶ to 65 cause the single flame of the Bunsen burner to ignite and burn in said aperture and spread and travel forward over the upper surface of the bottom A'.

A transverse air inlet slot A⁷ is formed between the lower edge of the rear end A⁴ and the bottom A' of the body A, and this slot A⁷ is directly below the entrance opening of the boss A⁶ and approximately in line with the upper surface of the bottom A', so that the 70 air entering in a thin sheet through the slot encounters the sides and undersides of the flame and by mixing with the burning gases insures complete combustion.

In order to deflect the intensely hot and expanding gases produced by the flame of the Bunsen burner downward and over the entire upper surface of the bottom of the iron, so that the heat may be absorbed by said bottom as much as possible before the said 85 gases are allowed to rise to the upper portion of the hollow body A, a deflector A⁸ is arranged within the hollow body A, and this deflector is preferably in the form of a plate spaced from the rear end and sides of the said 90 hollow body, extending in a forwardly direction and terminating a distance from the front end of the body A. The deflector is suspended from the top A³ by a lug A⁹ and screw A¹⁰, and extends directly above the 95 flame to prevent undue rise of the expanding and burning gases, but to deflect them downward and bring them in contact with the entire upper surface of the bottom of the iron. Said deflector is spaced from the sides A² and 100 the rear of the hollow body, to allow the products of combustion to rise freely into the upper portion of the hollow body, after being thus evenly distributed over the entire upper surface of the bottom of the iron, and to 105 pass forward above the partition to the draft-flue A⁵. A lug A¹¹ is located on the inside of the bottom A' of the iron, extending transversely thereof at a distance from the heel of the iron, to assist in spreading the 110 flame. The bottom A' is provided with corrugations A¹².

A handle E is attached to a protecting plate E', having lugs E² resting on the top A³ to space the plate E' from the said top, to keep the protecting plate E' and the handle 5 as cool as possible. A bolt F or other suitable means is employed for securing the plate E' to the top A³.

In using the sad-iron, the operator opens the cock C³ of the Bunsen burner, so that a 10 current of gas flows through the mixing chamber C' and in doing so draws in air at the air-intakes C⁴, to form with the gas a highly inflammable mixture which, in passing into the hollow body A and up the draft-flue, can be readily ignited at the terminal of the draft-flue A⁵. The gas mixture burning 15 in the hollow body causes a uniform heating of the bottom A', especially as but a single flame is had, which is spread and travels forward within the hollow body from the rear end thereof to the front end, the deflector spreading the flame and hot gases over the entire bottom A', the products of combustion 20 passing between said deflector and the sides of the iron upward into the upper portion of the hollow body and thence out of the draft-flue A⁵.

As the gas is completely burned within the body A, the sad-iron is rendered odorless, 30 and by the operator regulating the cock C³ and the valve C⁵, a more or less intense flame may be produced within the body A. It will be observed that the gas entering the enlarged bore of the boss A⁶ is ignited and commences to burn therein and a partial vacuum 35 is thus created in said enlargement, which draws in the air with great force through the air-intakes C⁴ rather than from the atmosphere surrounding the outlet of said enlargement. An intensely hot, blue flame of 40 blow-pipe effect is thus created, which enters the interior of the hollow body A at the extreme rear thereof, and is spread over the rear of the bottom of the iron by the lug A¹¹ and carried over the entire corrugated surface A¹² thereof, heating the same uniformly. 45 The deflector suspended in the center of the iron is so spaced from the interior walls as to give nearly the whole interior of the body 50 of the iron for the complete combustion of the gases, and forces the hot gases to pass all over the bottom of the iron, thus adding to the uniformity of the temperature, the products of combustion passing off through the 55 openings a⁵ in the sides of the draft-flue A⁵, which openings also afford a convenient place at which to light the iron.

As before stated, the front of the draft-flue A⁵ is closed, the sides only being open. This 60 prevents a backward draft of air when the iron is in motion. The hand which holds the handle is protected from the heat by the metal shield E' that is separated from the top of the iron by an air space, and the wooden 65 handle E is kept cool by being attached to

the shield, and is so arranged as to move the iron with a minimum expenditure of energy. Any desired temperature can be maintained by regulating the supply of gas and air, and the iron can be constructed in accordance 70 with the principles set forth above, so as to accomplish all these objects and to weigh not more than six pounds.

There are three principles to which it may be well to again call attention:

The first is the admission of a mixture of 75 gas and air through the mixing chamber C' into the enlarged aperture in the boss A⁶ in an unimpeded flow. The combustible mixture of gas and air is ignited and the process 80 of combustion commences to take place in such enlargement instead of at the outlet thereof. The gases burning in such enlargement create a partial vacuum which draws in air through the mixing chamber C' with 85 great velocity by way of the air-intakes C⁴, as the vacuum cannot be filled from any other direction except from the reverse of the current of gas and air, which is prevented by the great driving force of the flame, the same being similar to a blow torch in manner and effect. In this manner I obtain a very short 90 but strong, bluish-green Bunsen flame, containing as large a proportion of air as it is possible to combine with the combustible elements of the gas supplied,—in fact, as much air as can be used by a Bunsen tube supplied with air under artificial pressure.

The second principle is connected with the deflector, which does not extend from side to side of the iron, but is spaced from the side walls and from the ends of the irons, thus 100 while deflecting the heat toward the bottom of the iron still leaves substantially the whole interior of the iron a combustion chamber. 105 With my construction, the flame and hot burning gases are deflected downward and distributed evenly over the entire upper surface of the bottom of the iron, and at the same time the deflector allows the hot and burning 110 gases to rise into the upper portion of the hollow body after having been brought in contact with the surface of the bottom of the iron, and the combustion of any still unburnt 115 gases is here completed, the products of such combustion, without any odor or smell, passing out by the draft-flue A⁵. In this connection it will be observed that the enlarged opening a⁵ is inclined downwardly from the 120 gas supply and causes the flame to impinge upon the rear of the bottom of the iron; also that the lug A¹¹ is directly in the path of this flame, but does not extend entirely across the iron; this lug therefore assists in spreading the flame and causes it to penetrate to the 125 rear, outer corners of the iron, which would not be heated to the temperature of the rest of the bottom of the iron in the absence of the lug.

The third principle is the admission of air 130

through the rear or heel of the iron through a comparatively small orifice, admitting a draft under the flame which aids in consuming the gas.

5 The application and combination of these principles makes it possible to use a hollow body without draft-inlets of any description, except at the rear of the iron, the driving force of the flame being sufficient to draw in 10 at such rear draft-inlet enough air external to the flame to complete the combustion process commenced in the enlarged aperture in the boss above referred to; the driving force of the flame being sufficient to prevent any backward action when the iron is in motion. The 15 only outlet being at the top of the draft-flue, before reaching which point the combustion process has been completed, all possible chance of escaping flames coming into contact with the material to be ironed is eliminated. The above principles working together provide a uniform heat all over the bottom of the iron.

Having thus described my invention, I 20 claim as new and desire to secure by Letters Patent:—

1. A sad-iron comprising a hollow body provided with an exterior boss extending upwardly and outwardly from the lower portion thereof; and a gas mixer connected with said boss, said boss being provided with an enlarged opening or bore at its inner end forming a chamber outside of the body in which the gases are ignited and the combustion process is commenced; the burning of the gases in such enlargement before escaping therefrom creating a partial vacuum at such point, which in turn assists in drawing air through the mixer, said mixer 35 being provided with openings to the outer air.

2. A sad iron, comprising a hollow body open at the top and at the rear end, the bottom being corrugated and provided, a short distance from its rear end, with a transversely extending lug terminating short of the sides of the body, a top having a downwardly extending member forming the rear end of the body and provided at its front end with an air flue closed at the front 45 and having a lateral outlet, and with a depending lug on its inner face at about its center, the downwardly extending member of the top terminating short of the bottom of the body to form an air inlet and having a downwardly inclined tubular boss, a deflecting plate secured to the lug of the top, and terminating short of the ends and sides of the body, a handle having a bottom plate provided with lugs resting upon the top, 55 and means for securing the said plate to the top.

3. A sad iron comprising a hollow body open at the top and rear end, the bottom being corrugated and provided a short dis-

tance from its rear end with a transversely 65 extending lug terminating short of the sides of the body, a top having a right angular member forming the rear end of the body and provided with a depending lug on its inner face and at its front end with an upwardly projecting draft flue closed at its front end and having a lateral opening, the angular member of the top terminating short of the bottom of the body to form an air inlet and having a downwardly inclined tubular 70 boss, a deflecting plate secured to the lug of the top and terminating short of the ends and sides of the body, and a handle secured to the top.

4. A sad iron comprising a hollow body 80 open at the top and at the rear end, the bottom being provided near its rear end with a transversely extending lug terminating short of the sides of the body, a top having at its rear end a right angular member forming the 85 rear end of the body and provided with a lug on its inner face and with an upwardly projecting draft flue at its front end, the angular member of the top having a downwardly inclined tubular boss, a deflecting plate 90 secured to the lug of the top and terminating short of the ends and sides of the body, and a handle secured to the top.

5. A sad iron, comprising a hollow body open at the top and at one end, a top having 95 a right angular member forming the end of the body, and terminating short of the bottom thereof, said top being provided at its front end with an air flue, a depending lug on its inner face and an external tubular boss 100 projecting from its angular member, a deflecting plate secured to the lug of the top and spaced from the ends and sides of the body, and a handle secured to the top.

6. A sad iron, comprising a tubular body 105 open at the top and rear end, a top having a right angular member, forming the rear end of the body, said top being provided at its front end with a draft flue, a depending lug on its inner face and an external tubular boss 110 projecting from its angular member, the bore of the boss being in two diameters, the inner one being the larger, a deflecting plate secured to the lug of the top, and a handle secured to the top.

7. A sad iron, comprising a hollow body 115 having a draft flue projecting from the top at its front end, an external inclined tubular boss at its rear end, and a transversely extending lug on its bottom a short distance 120 from its rear end, said lug terminating short of the sides of the body, and a deflecting plate suspended within the body and spaced from the ends and sides of said body.

8. A sad iron, comprising a hollow body 125 open at the top and rear end, and a top having a right angled member at its rear end forming the rear end of the body and pro-

vided with a draft flue at its front end, said angular member being of a width equal to the distance between the sides of the body and extending to within a short distance of the bottom of the body to form an air inlet and provided with an exterior tubular boss.

In testimony whereof I have signed my

name to this specification in the presence of two subscribing witnesses.

JAMES E. AUSTIN.
